(57) **CLAIM**

The ornamental design for a video conference endpoint, as shown and described.

DESCRIPTION

FIG. 1 is a front perspective view of a video conference endpoint;

FIG. 2 is a top plan view of the video conference system endpoint of FIG. 1;

FIG. 3 is a bottom plan view of the video conference system endpoint of FIG. 1;

FIG. 4 is a front elevation view of the video conference endpoint of FIG. 1;

FIG. 5 is a rear elevation view of the video conference endpoint of FIG. 1;

FIG. 6 is a first side elevation view of the video conference endpoint of FIG. 1; and,

FIG. 7 is a second side elevation view the video conference endpoint of FIG. 1.

Any portions shown using dashed lines are for illustrative purposes only and form no part of the claimed design.

1 Claim, 7 Drawing Sheets
